UNITED STATES PATENT OFFICE.

LOUIS D. SUMMERS, OF SPRINGFIELD, ILLINOIS, ASSIGNOR TO FRANZ AND SUMMERS, OF SPRINGFIELD, ILLINOIS, CONSISTING OF FRED J. FRANZ, WILLIAM J. FRANZ, AND LOUIS D. SUMMERS.

BOILER AND ECONOMIZER ORGANIZATION.

Application filed March 1, 1926. Serial No. 91,312.

My invention relates to a boiler and an economizer connected thereto in such a manner as to secure through their cooperative relation a maximum benefit from the heated products of combustion, which normally pass out of the furnace as waste heat. An object of the invention is to provide means to produce a heated medium for a heating system quickly and without waiting for the entire mass of water in the boiler to warm up to its normal operative temperature.

The intended novel features of construction and design of my device will be herein-after more fully described in the annexed specifications, recited in the claims and illustrated in the accompanying drawings in which like reference numerals indicate the same structural parts in the several figures.

Referring to the drawings, Fig. —1— is a side elevation of the hot water and steam heat economizer of my invention illustrating the manner in which the same is connected with a hot water and steam furnace including both the hot water connections and the hot gas connections between the hot water furnace and the economizer.

Fig. —2— is a side elevation of the heat economizer of my invention shown detached from the furnace with which it is normally connected.

Fig. —3— is a side elevation of the heat economizer of my invention with the jacket removed from about the gas chamber of the economizer.

Fig. —4— is a side elevation of the hot water and steam heat economizer of my invention showing a cutaway exposing many of the hot water tubes of the economizer as well as other details of structure of the same.

Fig. —5— is a vertical section, taken on line *m*—*m* of Fig. —2—, of the economizer.

Fig. —6— is a horizontal cross section, taken on line *n*—*n* of Fig. —2—, exposing to view a possible arrangement of the hot water tubes in their space relation.

The preferred embodiment of my invention and the method of securing the desired results therewith will now be pointed out as references are made to the several numerals in the respective figures illustrating the device of my invention.

Among other successful arrangements by which intended results of my invention may be attained is an arrangement illustrated in

the accompanying drawings whereby the hot water and steam heat economizer —1— (Fig. —1—) is spaced from but operatively connected with a hot water furnace —2— by both hot water and hot gas connections.

A particular merit of my invention may be observed in the fact that flue pipe —3— of hot water and steam furnace —2— connects directly with the upper area of the gas chamber of the economizer —1— to which it carries the heated products of combustion from hot water or steam furnace 2. The hot gases, therefore, strike pipes 11 of the economizer at the top thereof, preferably immediately below drum 12.

In this manner it will be seen that the hot gases reaching chamber —10— from the hot water furnace —2— through flue pipe —3— reach this chamber when said gases are at a very high temperature and they arrive at the point where the first application may be most effectively made for the purpose of heating water rising in the pipes just before the water or steam therefrom is ready to be distributed throughout the heating system.

Every hot water system has a cold water return in the circulating system adapted to return the water after it is cooled to the lower portion of the boiler. This return pipe is not shown in Fig. —1— but a cold water pipe —5— connects the lower area of the boiler in furnace —2— with lower water chamber —13— through which the cold water entering the economizer through drum —9— forming chamber —13— rises through hot water tubes —11— with an accelerating velocity until it reaches upper chamber —12— from which it is distributed through pipe 6 and then through pipe —7— of the hot water furnace.

To those skilled in the art to which this economizer pertains it will be observed that this novel and efficient as well as speedy method of heating and distributing water or steam in this manner is accomplished in the following way: When the gases from flue pipe —3— forcibly enter chamber —10— accommodating the heated products of combustion they enter the upper area thereof and can only move in one direction upon entering this chamber and that is downward; and they move downward through heat stratification; and by actual test it has been shown that while these gases are settling

downward in the gas chamber they gradually give up a great percentage of their heat before passing out of pipe —4— to the chimney. It will therefore be seen that 5 while the gases through this process are gradually settling to a lower level in the economizer and giving up their heat as they settle and also settling because they are giving up their heat and getting cooler, the 10 water in the meantime entering the bottom of chamber —13— gets its first application of heat as it reaches the level of the bottom of the gas chamber and economizer where the gases are at their lowest temperature and 15 then as the water rises in the tubes to the level of the hotter gases it reaches its highest temperature substantially as it enters the hot water dome —12— before leaving the economizer as hot water or steam.

20 Attention is called to Figure —3— which exposes to view the upper and lower water chambers and their connecting water tubes. This is shown by the removal of jacket —1— which when secured into operative position forms the gas chamber about pipes —11—. This jacket is secured into place normally by bolts —15—.

25 This economizer is adapted to be supported on legs —14—.

30 To those skilled in the art it will be evident that certain changes might be made in

the details of structure of my economizer and still stay within the spirit and scope of my invention but the preferred arrangement of details is illustrated in the drawings 35 forming a part of this specification.

Having thus described the nature of my invention what I claim as new and useful and desire to secure by Letters Patent is:

I claim:

The combination, with a relatively large low pressure boiler of a flue for conducting the products of combustion therefrom, a relatively small economizer interposed in said flue and having an upper and a lower head and pipes connecting said heads, said flue comprising a section leading from the boiler to a point in the upper portion of the economizer adjacent said upper head, and a section leading to the stack from the economizer from a point adjacent the lower head, a pipe connecting the lower head of the economizer to the lower portion of a section of said boiler, an offtake pipe leading from the upper portion of said boiler, and a pipe connecting the upper head of said economizer to said offtake pipe.

In witness whereof I hereunto set my hand and seal this 16th day of January, A. D. 1926.

LOUIS D. SUMMERS.
